LINING FOR VESSELS

John Carlstrom, Port Arthur, Tex., assignor to
 The Texas Company, New York, N. Y., a corporation of Delaware

Application June 17, 1932, Serial No. 617,833

6 Claims. (Cl. 196—133)

This invention relates to interior linings for the protection of vessels in which the treatment of materials corrosive to the walls thereof may be carried on, and refers particularly to the lining of ordinary steel vessels used in the pressure cracking of hydrocarbon oil.

In the pressure cracking of petroleum fractions corrosive compounds are encountered or are developed in the decomposition process which attack the steel walls of the vessels in which the treatment is being carried on, which has the effect of deteriorating or corroding away the metal very rapidly.

In practice the shells of vessels of this class are fabricated of much heavier material than is necessary merely to withstand the temperatures and pressures ordinarily employed, for the reason that in the course of operation the interior surfaces of the walls are deteriorated to such an extent that their strength is materially impaired. Accordingly it has been necessary to allow for a certain amount of deterioration by making the walls of extra thickness. It will be seen that the expense of constructing large vessels is multiplied rapidly as the thickness of the shells is increased. It is therefore of advantage to provide an effective lining which is not corrosive to those constituents which attack a vessel and is adapted to protect the interior surface of a vessel, and which may be readily repaired or removed from and replaced in the vessel.

In instances where the coefficient of expansion of the lining material is less than that of the vessel, the vessel has a tendency to expand away from it in which event the lining, not being strong enough to withstand the pressure usually employed, may rupture or may be permanently expanded by the force of the pressure to a larger size and buckle when the temperature is next lowered to atmospheric. On the other hand where the coefficient of expansion of the lining is greater than that of the vessel it will have a tendency to bulge and buckle when the temperature is raised, in which event the lining may eventually rupture at the point of buckling.

I have discovered that in the pressure cracking of hydrocarbon oil it is not necessary to completely isolate the walls of the vessel from the inclosed oil or vapor and that moreover if certain of the products of reaction such as carbon or coke particles are permitted or added to deposit on the surface thereof they may form a protective coating which is itself resistant to corrosion. I have further discovered that corrosion often proceeds most rapidly from the clean surface of a

metal and that certain of the forming sulfides and other corrosion products may themselves, as a coating, be a protection against more advanced or continued corrosion of the steel walls. It is noted, however, that in the vapor space of cracking vessels, where corrosion is more pronounced, the walls of the vessel are normally swept relatively clean of any protecting film such as coke and that any protection against corrosion which would otherwise be afforded by deposits of coke or of corrosion products, such as sulfides, is thereby continuously destroyed.

The invention contemplates a relatively thin lining formed of a plurality of sections of non-corrosive sheet metal which is adapted to fully cover and protect the surface or portions thereof of the vessel to which it may be applied. The sections comprising the lining overlap thereby forming a continuous lining surrounding the interior wall of the vessel. The invention includes novel means for securing the protecting plates to the inner wall of the vessel which will permit the individual sections of the lining to expand or contract freely with changes in temperature independent of the wall of the vessel and which will also permit inexpensive installation or removal of the lining.

It is not necessary in all instances to line an entire vessel as frequently the portion occupied by the liquid is not subject to the severe corrosive conditions as is the portion occupied by the vapor. Accordingly the present description concerns specifically a partially lined vessel, although if desired the entire vessel may be lined.

An object of this invention is to provide a corrosive resistant liner adapted to contract and expand freely.

Another object of this invention is to provide a corrosive resistant lining made up of a plurality of independent sections, each of which is adapted to contract and expand freely.

The invention will be more fully understood by referring to the following description and the accompanying drawing in which:

Fig. 1 is a view in sectional elevation of a portion of a partially lined vessel showing a preferred embodiment of my invention.

Fig. 2 is an enlarged view in sectional elevation of the means for supporting the dome lining plates at their lower ends and the means for bracing the upper portion of the top row of wall lining plates.

Fig. 3 is an enlarged view in sectional elevation of the means for supporting the top row of wall lining plates at their lower ends and the means for

securing the upper ends of the next lower row of wall lining plates.

Fig. 4 is an enlarged view taken on the line 4-4 of Fig. 1.

5 Fig. 5 is a view in elevation of a typical clip which secures the lining plates to each other.

Fig. 6 is a view in elevation of a typical clip which secures the last lining plate to be installed in each row.

10 Referring now to Fig. 1, an upper section of a vertical cylindrical vessel having a convex end or dome is illustrated which may be used in the pressure cracking of hydrocarbon oil. The apparatus shown is intended to be that portion of a 15 vertical expansion chamber which is situated above a level of liquid carried in the vessel, which is usually referred to as the vapor space and in which the corrosive action of the existing vapors is especially pronounced. That portion of 20 the vessel shown comprises a shell portion 1, a manway 2, a pipe connection 3, a vapor outlet pipe 4 and the lining.

While I have shown a vertical cylindrical vessel having a convex end, it is to be clearly understood that my invention is not limited to a vessel shaped in this manner. The vessel may be of any shape and may be positioned in a horizontal or slanting position, if desired, without departing from the scope of my invention.

30 According to the invention the lining may include one or more circumferential rows of rectangular plate sections 10, depending upon the vertical dimension of the shell portion to be lined, and a top circumferential row of rectangular 35 plate sections 11. The plate sections 10 and 11 are individually rolled to fit the curvature of the shell and the adjacent vertical edges of the plates may overlap, as at 12, and the overlapping plates 40 may be snugly secured at any desired vertical intervals by metal clips 13 which are preferably fastened to the covered edge of each plate.

Referring to Fig. 3, a circular angle bar 17, which may be made up of arcuate sections of 45 mild steel, is preferably welded at its lower extremity to the shell 1 for supporting the plates 10. A circular flat bar 18 which may be in several arcuate sections to form a circular member is welded to the upper side of the horizontal extension of the angle 17 in spaced relation to the shell 50 1 for slidably securing the lower ends of and supporting the plates 11. A sectional flat bar 19, similar to the bar 18, may be welded to the lower side of the horizontal extension of the angle 17 for slidably securing the upper ends of the plates 55 10.

A circular angle bar 15 may be welded to the shell 1 in a manner similar to the angle bar 17 and a circular flat bar 16 may be welded to the upper side of the horizontal extension of the 60 angle bar 15 for securing the lower ends of and supporting the plates 10 in a manner similar to that in which the flat bar 18 and angle bar 17 secure and support the plates 11.

65 A number of metal clips 20 are preferably secured to the plates 11 near their upper ends for supporting a sectional flat bar 21, the ends of each section of which may be welded together to form a circle, which is provided to retain the plates 11 in proper circular alignment with the shell.

70 Segmental dome plates 25, the adjacent edges of which overlap, as at 26, are provided to form a lining for the convex end of the vessel. The dome plates may be supported at their lower or flaring ends by a plurality of clips 27 which are fastened

75 to the plates 11 above the clips 28. At the center point at the top of the dome, a disc-like plate 28 is preferably attached to the inwardly protruding vapor outlet pipe 4 by welding, as at 29. The plate 28 is adapted to overlap and support the upper or tapering ends of the dome plates 25 closely, but slidably against the dome.

80 A lining is provided for the manway 2 comprising a thimble or sleeve 30 which may be secured therein by welding the outer end to the neck of the manway, as at 31, and providing a flange or extension 32 adapted to overlap the lining plates.

85 The pipe connection 3, which in most cases is provided for communication to an adjoining vessel, may preferably be lined from one vessel through to the other. The lining consists of a sleeve 35 of such length as to project slightly past the inwardly protruding end of the connection 3. A disc-like plate member 36, whose surface is 90 compressed to form a circular concavity between the end of the pipe lining and the vessel lining, is welded at its inner edge to the end of the pipe lining, as at 37, and its peripheral edge presses against the vessel lining thus serving to protect 95 the end of the pipe connection where it is welded to the wall of the vessel.

100 In assembling the lining herein shown and described, the angle bars 15 and 17 are preferably first welded to the shell and the sections of the 105 bars 16, 18 and 19 are then welded to the angle bars. The plates 10 are next placed in position by forcing them upward behind the flat bar 19, which may be of greater width than the flat bar 16, and then dropping them behind the flat bar 110 16 to rest on the angle bar 15. The several plate sections are successively adjusted in place to cooperate with the previously placed plates by advancing the edges of the ones over the edges of the others in cooperative relationship with the 115 clips 13 of the previously placed adjacent sections. Referring to Figs. 4 and 6, it will be noticed that the clips of the last plate to be installed may be rotated to one side with the single rivet or screw being left somewhat loose, until after the plate 120 11 has been properly adjusted to position when they are returned to a position to clasp the overlapping edge of the adjacent plate and hammered or screwed tight.

125 In an alternative method of assembling the 130 lining the angle bars 15 and 17 may be welded to the shell and the several plate sections 10 may be successively adjusted in place and the bars 16 and 19 may then be located and welded to the angle bars 15 and 17, respectively, to thus secure the 135 plates 10 in proper relation to each other and to the vessel wall. Similarly in taking the lining apart sections of the bars 16 and 19 may first be removed after which the plate sections 10 140 may be withdrawn.

145 The plate sections 11 are placed and adjusted in somewhat the same manner as the sections 10 except the sections 11 are merely set in at their lower ends between the bar 18 and the wall and adjusted with relation to each other while 150 being supported upon the angle 17. As two or three sections 11 are placed and adjusted, an arcuate section of the circular flat bar 21 is dropped into the clips 20 to secure the plates in place. When all of the plates 11 are placed 155 and adjusted the several sections of the bar 21 are adjusted and welded together, the circular bar when complete being of such size as to secure the plates rather closely, though movable laterally, between the bar 21 and the wall.

The segmental dome plate sections 25 are next placed and adjusted, the circular plate 28 having been welded to the inwardly protruding vapor pipe 4 in appropriately spaced relationship to the dome. The tapering ends of the plate sections 25 are advanced upwardly far enough between the plate 25 and the dome for the flared ends of the plates 25 to clear the top of the support clips 27 and are then dropped down to rest upon the shoulders of the clips next to the plate sections 11. The successively placed plates 25 are moved laterally, when placed, to effect a sufficient overlapping of the adjacent edges. As a rule there is no vibration or sudden movement of vessels such as the one for which this lining is provided and as ample support is had at the flaring and tapering ends of the segmental plates, it is not deemed necessary to tie them together.

It will be seen that a lining has herein been provided which is not bonded to the shell at any point and which may expand and contract freely with changes in the temperature of the vessel. A lining is further provided which is constructed of a plurality of sections adapted to be readily removed from and replaced in the vessel as required. Moreover if desirable the lining may be extended throughout the entire vessel.

Because of these several structural novelties it is possible to use a chrome-steel alloy or a chrome-nickel-steel alloy or any other suitable metal or alloy whose coefficient of expansion is greater or less than that of steel and which is resistant to corrosion. For example, when applying the present invention it is possible to use an alloy of 18% chromium 8% nickel and 74% steel, commonly known as stainless steel, which is almost entirely resistant to corrosion by the compounds which are present in the ordinary run of petroleum or which may increase or develop in it in the cracking step, and whose coefficient of expansion is approximately 50% greater than steel.

From the foregoing, it will be seen that my novel type of lining may be applied to either new or old vessels. If the lining is used in conjunction with a new vessel, it will be unnecessary to make the vessel of extra thickness merely for the purpose of taking care of subsequent corrosion. Moreover, if a vessel has been in use for a period of time sufficient to corrode the interior thereof to such an extent that any extended future use would further corrode same and make it unsafe, my corrosive resistant liner may be installed and the vessel operated safely.

The various angle bars, clips and arcuate bars may be made from the same metal or metal alloy as the sections comprising the lining. By following this selection, the various parts for securing the lining in place will resist corrosion to the same extent as the metal or metal alloy of the lining and consequently will not have to be replaced when the lining itself is otherwise satisfactory.

While I have shown and described an interior lining for a vessel used in the cracking of hydrocarbon oils, it is to be clearly understood that my invention is not limited to this type of vessel. Obviously the invention is applicable to any type of vessel in which a liner is desirable whose coefficient of expansion may be greater or less than that of the vessel itself and may or may not be resistant to corrosion. Moreover, my invention is not limited to a vessel of ordinary steel as any metal or metal alloy of sufficient strength may be used to construct the vessel.

Obviously many modifications and variations of the invention as hereinbefore set forth, may be made, without departing from the spirit and scope thereof, and therefore, only such limitations should be imposed as are indicated in the appended claims.

I claim:

1. A vessel adapted to contain corrosive agents comprising a cylindrical hollow metal body having end enclosures forming a closed chamber, tubular connections communicating with the interior of said chamber, a plurality of metal sheets arranged circumferentially about a longitudinal section of the chamber wall and adapted to form a lining therefor, an annular bracket extending around the interior wall of said vessel, means securing said bracket to said wall, a vertically extending flange on said bracket spaced from the wall of said vessel to form an annular upwardly extending recess adapted to receive the one end of said metal sheets, a metal ring encircling the opposite end of said liner sheets interiorly thereof, means secured to said liner sheets for supporting said ring, and means interlocking adjacent longitudinal edges of said metal sheets to maintain said sheets in circumferential alignment.

2. A metal vessel adapted for use in the conversion treatment of hydrocarbon oils comprising cylindrical side walls and end walls forming an enclosed chamber, tubular connections communicating with said chamber, a plurality of metal sheets arranged circumferentially about a longitudinal section of said chamber and forming a lining therefor, an annular bracket secured to the wall of said chamber at one end of the longitudinal section, a longitudinally extending flange on said bracket spaced from said chamber wall and cooperating therewith to form an annular recess adapted to receive one end of said liner sheets, means at the opposite end of said liner sheets for holding said liner sheets in transverse alignment against the wall of said chamber, and means including latches for interlocking adjacent longitudinal edges of said liner sheets.

3. A metal vessel adapted for use in the conversion treatment of hydrocarbon oils comprising cylindrical side walls and end walls forming an enclosed chamber, tubular connections communicating with said chamber, a plurality of liner sheets arranged circumferentially about a longitudinal section of said chamber wall and adapted to form a liner therefor, a plurality of metal sheets forming a lining for one of said end walls having longitudinal edges converging toward the center of said end wall, an annular bracket secured to the interior wall of said chamber at the lower end of said longitudinal section, an upwardly extending annular flange on said bracket spaced from said chamber wall and cooperating therewith to form an annular longitudinally extending recess adapted to receive one end of each of said first mentioned liner sheets, a metal ring encircling said first mentioned metal sheets adjacent the opposite end thereof, means secured to said first named liner sheets for retaining said ring in position, means including latches for interlocking adjacent longitudinal edges of said first named liner sheets, means secured to said first named liner sheets for supporting the lower ends of said second named liner sheets, a central plate overlapping the converged ends of said last named liner sheets.

sheets, and means retaining said plate in position.

4. In a vertical cylindrical vessel having a convex end, an interior lining comprising a plurality of rectangular plate sections arranged in horizontal rows to surround the interior of the vessel, each of said sections having vertical and horizontal edges, the vertical edges overlapping and secured together, circular angle bars secured to the interior of the vessel for supporting the rectangular plate sections at the lower ends thereof, circular flat bars secured to said angle bars for loosely maintaining the rectangular plate section in position at the upper and lower ends thereof and permitting expansion and contraction independently of the vessel, segmental plate sections adapted to form a lining for the convex end, each of said plate sections having a flaring end and a tapering end, the flaring ends being supported by clips attached to the upper portion of the upper row of rectangular plate sections and the tapering end being secured by a circular plate secured at the center point of the convex end.
5. In a vertical cylindrical vessel having a convex end, an interior lining comprising a plurality of rectangular plate sections arranged in horizontal rows to surround the interior of the vessel, each of said sections having vertical and horizontal edges, each section overlapping at its vertical edges, clips attached to each rectangular section near one of its vertical edges adapted to clasp the overlapping edge of the adjacent plate section when assembled, circular angle bars secured to the interior of the vessel for supporting the rectangular plate sections at the lower ends thereof, circular flat bars secured to said angle bars for loosely maintaining the rectangular plate sections in position at the upper and lower ends thereof and permitting expansion and contraction independently of the vessel, segmental plate sections adapted to form a lining for the convex end having overlapping adjacent edges, and flaring and tapering ends, clips attached near the upper ends of the rectangular sections in the upper horizontal row adapted to loosely clasp and support the segmental plates at the flaring ends, a circular flat bar retaining the upper row of rectangular sections in alignment with the interior of the vessel, clips attached above the first mentioned clips for supporting the flat bar, and a circular plate secured at the center point of the dome for securing the segmental plates near their tapering ends.

traction independently of the vessel, segmental plate sections adapted to form a lining for the convex end, each of said plate sections having a flaring end and a tapering end, the flaring ends being supported by clips attached to the upper portion of the upper row of rectangular plate sections and the tapering end being secured by a circular plate secured at the center point of the convex end.

6. In a vertical cylindrical vessel having a convex end, an interior lining comprising a plurality of rectangular plate sections arranged in horizontal rows to surround the interior of the vessel, each of said sections having vertical and horizontal edges, each section overlapping at its vertical edge, clips attached to each rectangular section near one of its vertical edges adapted to clasp the overlapping edge of the adjacent plate section when assembled, circular angle bars secured to the interior of the vessel for supporting the rectangular plate sections at the lower ends thereof, circular flat bars secured to the angle bars for maintaining the rectangular plate sections in position at the upper and lower ends thereof and permitting expansion and contraction independently of the vessel, segmental plate sections adapted to form a lining for the convex end having overlapping adjacent edges, and flaring and tapering ends, clips attached near the upper ends of the rectangular sections in the upper horizontal row adapted to loosely clasp and support the segmental plates at the flaring ends, a circular flat bar retaining the upper row of rectangular sections in alignment with the interior of the vessel, clips attached above the first mentioned clips for supporting the flat bar, and a circular plate secured at the center point of the dome for securing the segmental plates near their tapering ends.

JOHN CARLSTROM. 40
